UNITED STATES PATENT OFFICE.

GEORGE A. SMITH, OF DERBY, CONNECTICUT, ASSIGNOR TO THE ROBERT N. BASSETT COMPANY, OF SHELTON, CONNECTICUT, A CORPORATION OF CONNECTICUT.

WIRE-FORMING MACHINE.

1,032,513.

Specification of Letters Patent. Patented July 16, 1912.

Application filed June 18, 1910. Serial No. 567,730.

To all whom it may concern:

Be it known that I, GEORGE A. SMITH, a citizen of the United States, residing at Derby, in the county of New Haven and 5 State of Connecticut, have invented a new and useful Improvement in Wire-Forming Machines, of which the following is a specification.

My invention relates to wire forming machines but more particularly to the forms around which the wire is bent, and its object is to provide a form in which the working surfaces or portions against which the wire bears most heavily can be removed and 15 replaced by a new portion, or can be adjusted or ground so as to present a new wearing surface to the wire.

Another object is to provide a stock or holder, upon which the form is mounted, 20 carrying suitable means for locking or adjusting the removable portions of the form.

I attain these and other objects of my invention in the preferred embodiment thereof set forth in the following description 25 and accompanying drawings in which like reference characters refer to corresponding parts.

In the drawings: Figure 1 is a perspective view of the stock having the form mounted 30 on the face portion thereof; Fig. 2, a side view partly in longitudinal section and showing the wire formed thereon, and Fig. 3, a transverse sectional view taken through Fig. 2.

In carrying out my invention I employ 35 a stock or holder which is usually carried by a reciprocating part of the machine so as to cause the form to advance through an opening in a plate and project beyond the 40 surface of the plate, in which position the wire is forced against the form thereby taking the desired shape or configuration. The form then recedes back through the plate, the wire which is already shaped being 45 swept off the form by the edges of the opening in the plate so that the plate will be clear for further operations of the machine, all of which is well known to those skilled in the art of wire forming machines.

This stock A is preferably formed of tool 50 steel and is provided with an offset portion B enlarged as shown at C, the side of which latter is reduced or cut away forming a shoulder E, for the purpose hereinafter 55 fully described.

Extending outwardly from the face or end of the stock A and preferably formed integral therewith are the body or web portions F and G of the form which may be of any suitable shape to form the wire article desired, but in the drawing I have shown them of such a shape that a loop will be formed especially adapted to be used for hose supporters. The edges of the body portions are cut away as shown at E', E², F' 60 and F². In the present instance the stock is provided with a bore H which extends through the offset portion of the same, and in which is mounted a drill rod I which is adapted to fit within the cut away portions 65 E² and F', of the body portions, so as to form the central enlarged bearing portion of the form and is locked therein by a set screw J working in a threaded bore J' formed in the stock. 70

A bore K is formed in the stock in which a drill rod L is mounted which is adapted to fit within the cut away portion F² of the body F, so as to form one of the bearing 75 portions of the form, and said rod is also locked in position by a set screw M working in a threaded bore M'.

Extending through the enlarged portion C are a pair of bores N which communicate with grooves N' formed in the side of the 80 enlargement C beyond the shoulder E, and in which are mounted drill rods O which extend through the bores, and are adapted to fit against the cut away portions E' of the body portion G, so as to form bearing 85 or wearing surfaces for the form. Arranged over the drill rods O is a locking plate P provided with grooves P' to receive the rod, and with a central opening P² registering with a threaded bore Q into 90 which is adapted to be screwed a locking screw R for clamping the plate P over the drill rods O, so as to lock the same in their 95 adjusted position.

From the foregoing description it will be 100 seen that I have provided a form in which the portions that are subjected to the greatest wear can be replaced or removed and ground, so as to present new bearing surfaces to the wire.

While I have shown and described a form 105 constructed to shape a certain wire article, it is of course understood that the form may be constructed to shape other articles desired without departing from the spirit 110

of my invention, and further while I have shown wire which is circular in cross section the form may be used to shape wire of a different cross section, and that the device 5 generally is susceptible to such modification as may fairly come within the scope of the appended claims.

Having thus fully described my invention, what I claim as new and desire to set 10 cure by Letters Patent is:—

1. A form comprising a stock having body portions provided with grooved edges projecting from the face thereof, and rods mounted in said stock fitting in said grooves 15 to present a completed form.

2. A form comprising a stock having body portions extending therefrom provided with grooved edges, rods adjustably mounted in said stock fitting in said grooved 20 edges, and means for locking said rods in said stock.

3. A form comprising a stock provided with body portions having grooved edges, said stock being provided with bores

registering with the grooved edges of said 25 body portions, rods mounted in said bores fitting within the grooves of said body portions to complete the form, and means for locking said rods in said stock.

4. A form comprising a stock having 30 body portions projecting from the face portion of said stock, the said body portions having their bearing edges cut away, and rods mounted in said stock and fitted against said cut away portions to present a 35 completed form.

5. A form comprising a stock having body portions extending therefrom, the said body portions having their bearing edges 40 cut away, rods mounted in said stock and fitted against said cut away portions to present a complete form and means for locking said rods in said stock.

GEORGE A. SMITH.
